FLANGE OILER

Joseph P. Ruth, Denver, Colo., assignor to The Ruth Company, Denver, Colo., a corporation of Colorado.

Application October 31, 1933, Serial No. 696,042

6 Claims. (Cl. 184—3)

This invention relates to improvements in flange oilers of the type employed with locomotives and railroad cars of different types.

It is well understood that when a locomotive enters a curve in the track, the centrifugal force operates to force the flanges of the wheels that are located adjacent the outer rail of the curve against the ball of the rail and if these flanges are not properly lubricated, they will wear very fast and sometimes the frictional resistance will be sufficiently great to cause the flange to raise the wheel sufficiently to make the engine jump the track. The jumping of the track is an extreme case which does not occur except in exceptional circumstances, but the wear of the flanges is a fact that must be considered at all times.

I am aware that many different mechanical expedients have been resorted to for the purpose of lubricating the flanges of locomotive drive wheels, but the great majority of these are so constructed that the lubrication is a continuous process and therefore a large amount of lubricant is wasted as it is not necessary to lubricate the flanges when the train is traveling over a straight track.

It is the object of this invention to produce a lubricating device that shall be operative only when the locomotive enters the curved part of the track and which shall continue the lubrication for a sufficient length of time to assure that the flanges are properly lubricated during the whole time that the curve is being traversed.

Another object of this invention is to produce a device that shall automatically lubricate the flanges on the outside of the curve, because it is obvious that the flanges which do not engage the rails do not require lubrication and therefore if both sides are lubricated at all times, there is a waste of fifty per cent of the lubricant employed.

The above and other objects which may appear as this description proceeds are attained by means of a construction and an arrangement of parts that will now be described in detail and for this purpose reference will be had to the accompanying drawing in which the preferred embodiment of the invention has been illustrated, and in which:

Fig. 1 is a top plan view, partly in section and partly broken away, showing the front part of drive wheels and a part of pilot wheels attached to a locomotive frame;

Fig. 2 is a view looking in the direction of arrows 2—2, in Fig. 1 and shows a front elevation

of the parts illustrated in Fig. 2, portions of the housing and frame being broken away to better disclose the construction:

Fig. 3 is a diagrammatic view, partly in section, showing the relation of the several parts that form the combination which constitutes this invention;

Fig. 4 is a side view to a small scale of a locomotive and illustrates one type of vehicle to which this invention can be applied; and

Fig. 5 is a section through an accumulator or pressure chamber which can be substituted in the combination for the air chamber shown in Fig. 3.

In the drawing reference numeral 6 indicates members of the vehicle frame and these have been shown in part only and are illustrative of the entire frame employed. The frame is supported on a plurality of axles 7, to the ends of which drive wheel 8 are connected. The drive wheels shown in Fig. 1 and indicated by reference numeral 8 are the ones nearest the pilot wheels 9, and where the locomotive is so constructed that it can travel with equal facility in either direction, there are two pair of drive wheels corresponding to those indicated by numeral 8. The front end of the frame has been designated by reference numeral 10 in Fig. 2 and extending downwardly from the outer side of the frame are brackets 11 and 12. These brackets have cooperating channels 13 that form guides for the boxing 14. Pilot wheels 9 are secured to the ends of an axle 15 that passes through a bearing housing 16 in

which it is mounted by means of roller bearings of the "Timken" type. The bearing housing is provided at each end with a cylindrical recess, the outer walls of which have been designated by reference numerals 17. Extending inwardly from the parts 17 are lugs 18 that are perforated for the reception of pivot pins 19. Secured to the pivot pins 19 are links 20, there being a pair of links for each lug. Springs 21 have their ends secured by means of pivots 22 to the lower ends of the links 20 and the distance between the pivots 22 is shorter than the distance between the pivots 19 so as to produce a force that automatically tends to maintain the axle housing 16 in central position. The weight of that portion of the frame which is supported by the pilot wheels rests on the springs at the central point

and is transmitted to the springs by the parts designated by reference numeral 23. Since the axle housing 16 floats in the casting 14 and has the weight suspended from the lugs 18 by links 20, it is evident that when force is applied to either

of the flanges 25 of the pilot wheels, the pilot wheel assembly will be moved transversely of the frame, the extent of this transverse movement depending on the curvature of the track or on the 5 value of the force applied to the flanges.

It is evident that when a locomotive constructed as indicated in the drawing travels along a perfectly straight track, the tendency is for the locomotive to so position itself that very little 10 force is exerted on the flanges and if the locomotive moves from one side to the other, it is brought back to neutral position without any severe strains on the flanges. When a locomotive 15 enters a curve, the pilot wheel will be the first to engage the inner surface of the outer rail of the curve and will be moved transversely of the frame to an extent, depending upon the radius of curvature employed and the distance from the axis of the pilot wheel to the axis of the first pair 20 of drivers. As soon as the locomotive enters on a curve, the outer drive wheel near the front end will have its flange forced against the ball of the outer rail and it is then necessary to apply a lubricant to this flange so as to reduce the friction 25 between it and the rail.

For the purpose of lubricating the flange of the front driver on the outside of the curve, the mechanism which will now be described has been provided.

30 Secured to the lugs 18 or to any other part that moves with the housing 16 is a bracket 26 that is provided with a threaded opening through which the bolt 27 extends. A lock nut 28 is connected with the bolt for the purpose of holding 35 it in adjusted position. Secured to parts that are stationary with respect to the frame are pumps which have been indicated in their entirety by reference numerals 29. Each pump is fastened to a bracket 30 that projects from some part of 40 the frame and is provided with a cylinder 31 in which is mounted a piston 32. A spring 33 acts on the piston to move it towards the right in Fig. 3 and a piston rod 34 is attached to the piston and extends through one end of the cylinder and 45 terminates in a head 35. The outer end of the piston rod may be enclosed in a rubber bellows 36 that protects the parts against the entry of dust and dirt. When no force is applied to the head 35, the piston remains substantially in the position 50 shown in Fig. 3, but if the piston rod and piston are moved towards the left, the contents of the piston chamber will be forced outwardly through the discharge port and into the conduit 37 which is provided with a check valve 38 that 55 prevents the lubricant from returning to the pump but which permits it to travel outwardly towards the end of the conduit. Conduit 37 has connected with it an air chamber 39 like those usually employed in connection with hydraulic 60 rams and force pumps. Extending from the air chamber is a flexible tubing 40 which is connected with a nozzle portion 41 that is held in a fixed position relative to the flange of the drive wheel by a bracket 42. The storage tank for the 65 lubricant has been designated by reference numeral 43 and this is connected to the intake portion 44 of the pump by means of a conduit 45 and a check valve 46 is interposed between the pump and the storage tank to prevent the lubricant from being forced back into this tank when 70 the pump operates.

75 It will be seen from Fig. 3 that a space 47 is provided between the head of the bolt 27 and the head 35 on the piston rod and therefore the pilot wheels may have a limited transverse move-

ment without effecting the operation of the pump. This limited movement is designed to take care of the slight transverse movement that will normally occur when the locomotive travels along a straight track and where the curvature is very small. The space 47 can, of course, be adjusted to any value desired by merely changing the position of the bolt 27. In Fig. 5 a slightly different form of compression chamber has been shown than the one illustrated in Fig. 3 and designated by reference numeral 39. The compression chamber or air chamber 39 depends upon the trapped air to produce the required pressure, whereas in the embodiment shown in Fig. 5, a cylinder 48 is provided in which is mounted a 15 piston 49 that is normally held in its lowermost position by means of a helical spring 50 whose upper end abuts the inner side of the cap 51. The two pressure chambers illustrated are considered to be equivalent for the purposes under 20 consideration and whenever reference is made to an air chamber or pressure chamber, it is intended to be broad enough to cover both of these or any other mechanical equivalent.

Let us now assume that the lubricating device 25 above described and illustrated in the drawing has been applied to a locomotive. When a locomotive is travelling along a straight track, the parts are in the position shown in Fig. 2, from which it will be seen that the bolts 27 do not come 30 into contact with the heads 35 and therefore the pilot wheels may move transversely to a limited extent without operating the pump. As soon as the locomotive enters on a curve the pilot wheel on the outside will be forced inwardly and 35 the bolt 27 will engage the head 35 and move the pump piston towards the bottom of the cylinder, thereby forcing lubricant from the piston chamber through the pipe 37. Since this motion is very abrupt, the pump will transfer a 40 large quantity of lubricant in a very short time and since the opening in the nozzle is much too small to take care of this amount of lubricant, it will be forced into the air chamber 39 and 45 compress the air therein. The check valve 38 functions to prevent the lubricant from returning to the pump. If the compression chamber illustrated in Fig. 5 is used, the lubricant will 50 force the piston upwardly, thereby compressing the spring and therefore after the pump has returned to normal position, lubricant will continue to be forced out of the nozzle by the pressure exerted on it by the compressed air or by the piston 49. By properly proportioning the capacity of the 55 pump and the capacity of the compression chambers, one single stroke of the pump will be sufficient to maintain a stream of lubricant against the flange 25 for any length of time desired, and this length is usually computed in such a way that it will take care of the average length of 60 curve, and perhaps a little more, because it is not necessary to lubricate the flange for the entire time it is in contact with the rail, and therefore by having the time just right for the average length, it will be sufficient in a practical way 65 for any curve.

As soon as the bolt 27 returns the spring 33 will move the piston to the position shown in Fig. 3, whereupon lubricant will be transferred from the storage tank 43 to the piston chamber and the 70 pump will be primed and ready to discharge a quantity of lubricant whenever the piston is moved inwardly by the action of the pilot wheels.

Since it is necessary to lubricate only one side at a time, and since the tracks may curve in 75

either direction, two pumps and two nozzles have been provided and only one of these function for each curve.

Particular attention is called to the fact that with this lubricating device no steam is employed and no compressed air except the air that is contained in the compression chamber 39.

Attention is also directed to the feature of construction described above whereby a single and almost instantaneous operation of the pump will set up forces that will produce a continuous spray of lubricant for a sufficient time to traverse the ordinary length of curve.

Although this invention has been described in connection with locomotives, it can be employed on street cars or passenger coaches and in fact in connection with any vehicle operated on railroad tracks.

Having described the invention what is claimed as new is:

1. In a locomotive, in combination, a frame, a plurality of pair of drive wheels attached to the frame, a pair of pilot wheels attached to the front end of the frame, the pilot wheels being attached to an axle and mounted for limited transverse movement with respect to the frame, and means operated by the transverse movement of the pilot wheel assembly relative to the frame for applying a lubricant to the flange of a drive wheel.

2. In a locomotive, in combination, a frame, a plurality of pair of drive wheels forming supports for the frame, a pair of pilot wheels attached to the front end of the frame, the pilot wheels being attached to an axle and mounted for limited transverse movement with respect to the frame, a storage tank for a lubricant, a pump having an intake and an outlet port, a conduit extending from the storage tank to the intake port of the pump, a conduit extending from the outlet port of the pump to a point adjacent a drive wheel flange, and means operated by the transverse movement of the pilot wheel assembly relative to the frame for operating the pump and transferring lubricant to the flange of a drive wheel.

3. In a locomotive, in combination, a frame, a plurality of pair of drive wheels forming supports for the frame, a pair of pilot wheels attached to the front end of the frame, the pilot wheels being attached to an axle and mounted for limited transverse movement with respect to the frame, a storage tank for a lubricant, a pump having an intake port in communication with the tank and an outlet port in communication with a conduit extending to a point adjacent a drive wheel flange, an air compression chamber having its lower end in communication with the last named conduit, and means operated by the transverse movement of the pilot wheel assembly relative

to the frame for operating the pump and transferring lubricant to the flange of a drive wheel.

4. In a locomotive having a frame supported on a plurality of pairs of drive wheel assemblies, and having its front end provided with a pair of pilot wheels secured to opposite ends of an axle, means for attaching the pilot wheel assembly to the frame in such a way that it can move transversely of the frame to a limited extent when the locomotive enters a curve, a storage container for a lubricant, a pump having an intake and an outlet port, a pipe connecting the intake port with the storage container, a discharge pipe extending from the outlet port to a point near the flange of a driver, the discharge end of the pipe having a nozzle provided with a restricted opening, an expandable pressure chamber in communication with the discharge pipe, and means for operating the pump for forcing the lubricant into the discharge pipe and pressure chamber when the pilot wheel assembly moves transversely of the frame beyond a predetermined limit.

5. In a railroad vehicle having flanged wheels for cooperating with the rails of a track, in combination, a frame, a plurality of flanged drive wheels forming a support for the frame, a pair of pilot wheels attached to the front end of the frame and mounted for limited transverse movement with respect to the frame, means comprising a pump for applying a lubricant to the flange of a drive wheel when the pilot wheels move transversely of the frame beyond a predetermined limit, and means for continuing the application of lubricant for a short time after the pump has ceased to function.

6. In a railroad vehicle having flanged wheels for cooperating with the rails of a track, in combination, a frame, a plurality of flanged drive wheels forming a support for the frame, a pair of pilot wheels attached to the front end of the frame and mounted for limited transverse movement with respect to the frame, a pump carried by the vehicle, said pump having an intake and a discharge port, a storage tank for lubricant, connected with the intake port, a discharge pipe connected with the discharge port and terminating in a nozzle adjacent the flange of a drive wheel, there being a closed chamber of variable capacity connected with the discharge pipe between the pump and the nozzle, means within the chamber for applying a pressure to the lubricant that enters thereto, and means operated by the transverse movement of the pilot wheels for operating the pump and forcing liquid into the pressure chamber whereby a single stroke of the pump will produce a stream of lubricant from the nozzle which will continue some time after the pump has stopped.
